UNITED STATES PATENT OFFICE.

ALONZO LIVERMORE, OF ASHLAND, PENNSYLVANIA.

IMPROVED FISHWAY.

Specification forming part of Letters Patent No. 57,159, dated August 14, 1866.

To all whom it may concern:

Be it known that I, ALONZO LIVERMORE, of Ashland, in the county of Schuylkill and State of Pennsylvania, have invented a new and Improved Fishway; and I do hereby declare that the following is a full, clear, and exact description thereof, which will enable others skilled in the art to make and use the same, reference being had to the accompanying drawings, forming part of this specification, in which—

Figure 1 is a longitudinal central section of my invention. Fig. 2 is a face view of one of the partition-walls.

Similar letters of reference indicate like parts.

My invention consists in constructing a fishway of any desired diameter, divided off into compartments to form pools or water-chambers, an opening being made through each division-wall for the current to pass through, and around these openings there are secured water-breaks, in the form of lips or tubes, pointing obliquely and against the current, by which construction and arrangement the velocity of the current is deadened or broken, causing counter-currents opposed to the efflux through the succeeding division-wall or lip C.

A designates a pipe or tank, of nearly equal size throughout its length. In the present instance it is tubular in form and spherical in cross-section; but it may be of any desired shape or size—say four feet in diameter would be a desirable size. This is divided into compartments by division-walls B, there being as many walls, and consequently compartments, as found most practicable. A pipe of one hundred and sixty-four feet could, with advantage, be divided so as to form twenty-five compartments. Through these division-walls B there is made a suitable-sized opening, and a projecting pipe or lip, C, formed around such openings on one side—namely, that which faces the current. These lips or tubes point slightly downward or to one side when the fishway is in a proper position for use. They serve as a water-break to check the rapid course, as can be readily understood.

I think it well in practice to make the opening a little to one side of the center of the partition-walls, which will tend the better to accomplish the last-named feature.

To illustrate, we will suppose the fall to be ten feet. The theoretical velocity of a ten-foot fall is 25.38 feet per second, which divided by the square root of the number of the divisions—say twenty-five—of the fishway will give the velocity of the water theoretically through each pipe or tube C, which will be 5.076 feet per second. The velocity in the larger compartments would be much less, the average of which would be, in this case, one-fourth of the velocity of the smaller pipes, or in proportion to the cross-section of the tubes or pipes C.

It is important that the rise should not be too great at the openings, lest the gravity or weight of the fish in ascending from one chamber to the other be too much for its power to overcome it, including the force of the water in its current, &c. In the case of a ten-foot rise divided into twenty-five divisions, the rise of each pipe or tube C would be 0.40 of a foot. The power exerted must be sufficient to raise the weight of the fish, together with the pressure of the water and momentum of the same.

The internal openings or tubes are projected toward the current, but obliquely, so as to avoid the direct action of the water, which passes upon one side and expends its force upon the side of the next succeeding division-wall, thereby destroying its momentum and producing a minimum contraction of the fluid vein. This minimum contraction will probably reduce the theoretical discharge to a little over one-half, or, say, from fifty-three to sixty per cent. This contraction will take place from the entrance of the water at the head of the discharge-pipe, and of course will be maintained throughout.

It is important that the tubes C be of uniform size, as near as may be, in order to maintain a uniformity of discharge in the tubes. It is not important that the main pipe be straight, nor is it necessary that it be inclined, as shown in the drawings.

The pipe may have bends and may be level, should it be more convenient to so construct it always, however, giving the fish abundant room to change their course.

I will here remark that the same principle of construction may be applied to any fluid or other conduits where great velocities are to be reduced. This would apply to pipes having the fluid to be discharged at a great elevation,

or vessels of liquor which are surcharged with gas. In any case the discharge could be regulated in the same manner as above described—to wit, by introducing within (say at the lower end of) the pipe such number of division-walls and enlargements as is desirable to reduce the discharge to a required minimum.

Having thus stated my invention, what I claim as new, and desire to secure by Letters Patent, is—

Constructing a fishway or other conduit

with division-walls built transversely to its length, and openings through said division-walls, and tubes or lips projecting therefrom in an oblique direction and against the current, by which construction the velocity of the current can be decreased as may be desired.

ALONZO LIVERMORE.
